FORCE-FEED BRUSH WITH SHORT
BRISTLES

Robert S. Eisner, Red Bank, and Morris R. Galle,
Little Silver, N. J.; said Galle assignor to said
Eisner

Application May 11, 1950, Serial No. 161,462

4 Claims. (Cl. 15—128)

1

This invention relates to brushes of the type used for applying paint and other coating materials to surfaces, such as walls and ceilings. More particularly, the invention is concerned with a novel brush, which although containing relatively short bristles, can be used as easily as brushes with much longer bristles in applying smooth, continuous coats of paint, etc. Since the bristles in a brush represent a large part of the cost of manufacture of the brush and the bristle cost increases rapidly with their length, it will be evident that the cost of the new brush is much less than that of prior brushes of comparable performance.

A smooth uniformly thick coat of paint or similar materials may best be applied manually by means of brush having bristles of a substantial length, such as 4" to 6". In such a brush, the bristles are secured at one end to a handle block with a blank space in the middle of the bristles and the free ends of the bristles meet in front of the block, thus leaving a space for holding paint inwardly from the ends of the bristles and surrounded thereby. In the use of such a brush of the dip type the bristles are dipped into the paint, so that a quantity of the paint enters the space within the bristles, after which the bristle end of the brush is applied to the surface to be coated and the brush is moved back and forth. In this operation, the bristles are flexed so that the sides of the bristles contact the surface and the larger the length of the bristles lying against the surface, the smoother is the coat applied. It is, thus, desirable to use a brush having bristles of such length that they may be easily flexed, but a brush of sufficiently long bristles for easy flexure is very expensive.

The present invention is, accordingly, directed to the provision of a brush, which can be produced at low cost because of having relatively short bristles, but is so constructed that, in use, the sides of the bristles may be caused to contact the surface to be coated over substantial lengths of the bristles. The desired results are obtained by constructing the brush with a head having a handle attached thereto, and a block spaced from the head and having a group of bristles secured to the block to encircle the block laterally. The head and block are secured together by flexible means, including a sleeve of a material, such as sheet synthetic rubber, the sleeve encircling the head and block laterally and being secured to the head. Although the bristles in the new brush are of relatively short length and consequently somewhat stiff, the

2

means connecting the head and block can be readily flexed in the use of the brush to cause the sides of the bristles to engage the work surface and thus produce a smooth coat of material thereon.

The new brush may be of the dip or fountain types and a form of fountain brush embodying the invention will be illustrated and described in detail for purposes of illustration.

10 For a better understanding of the invention, reference may be made to the accompanying drawing, in which:

Fig. 1 is a view, partly in vertical section and partly in elevation, of a fountain brush of the

15 invention; and

Fig. 2 is a sectional view on the line 2—2 of Fig. 1.

The brush illustrated comprises a head block 10 having a recess 11 formed in its upper side 20 to receive the bifurcated end portions 12 and 13 of a removable handle 14. A nipple 15 for coupling the handle to the head block is mounted in an opening through the head block and the nipple has a threaded lower end 16 projecting 25 beyond the lower face of the head block and an upper threaded end 17 projecting into recess 11.

A passage 18 extending longitudinally through handle 14 has a lower enlarged portion 19, into which is threaded a coupling member 20 provided 30 with a flange 21 spaced from the adjacent part of the handle to support a coupling nut 22 which is internally threaded. The handle is secured to the head block by placing its bifurcated portions in recess 11 and then screwing coupling nut 22 down upon the upper portion 17 of nipple 15.

The lower face of coupling member 21 and the upper face of portion 17 of the nipple are machined to engage with one another to make a fluid tight seal, or, in the alternative, a gasket (not shown) may be employed to prevent the leakage of fluid between the parts. The outer face of coupling nut 22 is knurled for easy turning, when the handle is to be detached from the head block or secured thereto. Flow of fluid 40 through the handle to the brush is controlled by a valve mounted in the handle and provided with an actuating member 23.

A feed block 25 having an inlet 26 in its upper face is attached to head block 10 to lie at a distance therefrom. For this purpose, threaded metal ferrule 27 is threaded part-way into the upper end of inlet 26 and a flexible tube 28, preferably of synthetic rubber, has one end fitted over the lower threaded end of ferrule 27 and secured to it by a nut 29, and its other end fitted

over the exposed end of threaded ferrule 27 and secured to it by a nut 30.

A group of bristles 31 is secured to the feed block 25 by having the upper ends of bristles embedded in a body 32 of material, such as a hard-setting rubber compound, which is secured to the feed block to encircle it. A plurality of discharge passages 33 extend divergently from the inlet 26 through the feed block to open at the lower face thereof, so that paint or other fluid supplied to the feed block through handle 14 and conduit 28 will be evenly distributed among the bristles.

A casing or sleeve 35 of flexible material and preferably of synthetic rubber, is secured to the head block by tacks 34 and, laterally, completely encircles the head block, the feed block and the space between the two blocks. Sleeve 35 supplies to the feed block a lateral positioning effect substantially similar to that provided by the main body of long bristles in conventional fountain brushes such as that disclosed in our Patent No. 2,454,553, issued November 23, 1948. Sleeve 35 and tube 28 can also be readily flexed in the use of the brush to cause the sides of the bristles 31 to engage the work surface and thus produce a smooth coat of paint or other material thereon.

We claim:

1. A brush which comprises a head having a passage therethrough, a handle attached to the head at one side thereof and having a passage through it which is aligned with the passage through the head, a block spaced from the opposite side of the head and having a passage through it, a group of bristles attached to the sides of the block to encircle the latter, a flexible tube connecting the passage in the head to the passage in the block, and a sleeve of flexible sheet material overlying the head and the block and enclosing the space between them, through which the tube extends, the sleeve being attached to the head and loosely engaging the block.

2. A brush which comprises a head having an opening therethrough, a nipple mounted in the opening and having its opposite ends extending outwardly from opposite sides of the head, a handle attached to the head at one side thereof by being secured to the end of the nipple extending from that side, said handle having a passage through it which is in alignment with the nipple, a block spaced from the opposite side of the head and having an inlet opening therein, a flexible tube connecting the other end of the nipple extending from said opposite side of the head to said inlet in said block, a group of

bristles attached to the sides of the block to encircle the latter, and a sleeve of flexible material laterally encircling the head and the block and attached to the sides of the head.

5 3. A brush which comprises a head having an opening therethrough, a nipple mounted in the opening and having its opposite ends extending outwardly from opposite sides of the head, a handle attached to the head at one side thereof by being secured to the end of the nipple extending from that side, said handle having a passage through it which is in alignment with the nipple, a block spaced from the opposite side of the head and having an inlet opening therein, 10 a flexible tube connecting the other end of the nipple extending from said opposite sides of the head to said inlet in said block, a group of bristles attached to the sides of the block to encircle the latter, and a sleeve of flexible material laterally encircling the head and the block and attached to the sides of the head, said block having a plurality of discharge passages extending divergently from the inlet opening and opening at the face of the block opposite from that which 15 contains the inlet opening.

4. A brush which comprises a head having an opening therethrough, a nipple mounted in the opening and having its opposite ends extending outwardly from opposite sides of the head, a handle attached to the head at one side thereof by being secured to the end of the nipple extending from that side, said handle having a passage through it which is in alignment with the nipple, a block spaced from the opposite side of the head and having an inlet opening therein, a threaded metal ferrule threaded part-way into the inlet opening, a flexible tube secured at one end to the other end of the nipple extending from said opposite side of the head and at its other end to the metal ferrule, a group of bristles attached to the sides of the block to encircle the latter, and a sleeve of flexible material laterally encircling the head and the block and attached to the sides of the head.
